UNITED STATES PATENT OFFICE

OATMER GERMOND, OF SOUTH BEND, WASHINGTON

CENTRIFUGAL GOLD AND MINERAL SEPARATOR

Application filed September 11, 1930. Serial No. 481,283.

This invention relates to a machine designed for recovering gold and other precious minerals from ocean or beach sand.

The primary object of the invention is the provision of a machine of this character embodying a stationary worm or spiral, and a tubular casing in which the worm or spiral is positioned, means being provided for rotating the tubular casing around the worm or spiral to cause the material to feed through the machine and accomplish the purpose of the invention.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a side elevational view of a machine constructed in accordance with the invention.

Figure 2 is a front elevational view of the machine.

Figure 3 is a longitudinal sectional view through the machine.

Figure 4 is a plan view of the machine.

Figure 5 is a sectional view taken on line 5-5 of Figure 3.

Figure 6 is a sectional view taken on line 6-6 of Figure 3.

Referring to the drawings in detail, the device comprises a body portion 5 that has a tapered lower end portion 6 that terminates in a straight section 7 in which the valve 8 is positioned, which valve controls the passage of material through the body portion 5.

Secured within the body portion 5 and arranged adjacent to the upper end thereof, is a bearing member 9 in which the upper end of the tubular casing 10 is mounted, the tubular casing 10 being shown as formed with an enlarged upper end portion 11 to support the tubular casing.

A bearing member indicated at 12 is also

secured within the body portion at a point in spaced relation with the bearing member 9, the latter bearing member also acting as a support for the tubular casing 10.

Openings 13 are formed in the body portion 5 and are disposed at points substantially intermediate the ends of the body portion 5, the openings being provided to allow material to pass from the body portion 5.

Secured to the upper end of the body portion 5, is a frame 14 to which the funnel 15 is connected, the funnel being provided with a lower flange 16 cooperating with the flange 17 of the tubular casing 10 to prevent material from passing between the upper end of the tubular casing and member 15. The lower end of the tubular casing 10 is closed by means of the cap 18, to prevent the passage of material directly through the tubular casing. Openings 19 are formed in the tubular casing and are spaced from the cap 18, to permit material to pass laterally from the tubular casing. Disposed within the tubular casing 10 is a stationary worm or spiral 20 which is formed with a shaft 21 that extends upwardly through the frame 14, where it is secured against movement by means of the collar 22 which is keyed to the shaft 21 by means of the bolt 23.

An opening 24 is formed in the body portion 5 to accommodate a power gear not shown, which gear is designed to mesh with the pinion 25 that is keyed to the tubular casing 10, to the end that rotary movement may be imparted to the tubular casing, by any suitable power device.

From the foregoing it will be obvious that due to the construction shown and described, material may be fed into the funnel 15, from where it gravitates into the tubular casing 10, which is rotated.

As the tubular casing rotates around the stationary worm 20, the material will be agitated and forced laterally through the openings 19, from where it passes into the body portion 5.

The material passes into the body portion and collects in the body portion until it reaches the openings 13, from where the material passes outwardly to a place of deposit.

It is obvious that the heavy particles of gold or metal will fall to the bottom of the body portion, from where the same may be removed through the valve 8.

5 I claim:

A machine for recovering precious metals from sand, comprising an elongated body portion having a tapered lower end providing a restricted lower portion, a rotary tubular casing within the body portion, the lower end of the casing extending into a restricted end of the body portion, a cap removably mounted on the lower end of the casing, and normally closing the lower end of the casing, 10 said casing having openings above the cap to allow material to pass laterally from the casing, a spiral mounted within the casing, and means for rotating the casing around the spiral to force material to the lower end of 15 the casing.

In testimony that I claim the foregoing as my own, I have hereto affixed my signature.

OATMER GERMOND.
